UNITED STATES PATENT OFFICE.

MICHAEL A. FOSTER, OF ST. LOUIS, MISSOURI.

GRATE FOR STEAM-BOILER FURNACES.

SPECIFICATION forming part of Letters Patent No. 331,700, dated December 1, 1885.

Application filed May 8, 1885. Serial No. 164,780. (No model.)

To all whom it may concern:

Be it known that I, MICHAEL A. FOSTER, of the city of St. Louis, in the State of Missouri, have invented a certain new and useful Improvement in Grates for Steam-Boiler Furnaces, of which the following is a full, clear, and exact description, reference being had to the accompanying drawings, forming part of this specification, and in which—

10 Figure 1 is a vertical section of the lower part of an upright furnace, showing my improved grate in elevation. Fig. 2 is a horizontal section of the grate, taken on line 2 2, Fig. 3, looking down. Fig. 4 is a vertical section taken on line 3 3, Fig. 2. Fig. 5 is a detail perspective view of the shaker-bar. Fig. 5 is a top view showing the vertical part of my furnace-grate applied to a horizontal grate adapted to a horizontal furnace.

20 My invention is an improved grate in which is combined a vertical with a horizontal part; and my invention consists in features of novelty hereinafter fully described, and pointed out in the claims.

25 Referring to the drawings, A represents the bottom of the furnace, and B the inner and outer walls of an upright boiler. (See Fig. 1.) On the bottom or base A of the furnace rests a horizontal grate, C, consisting, preferably, 30 when used for upright boilers, of two concentric rings, C' C'', connected by cross-bars C''. The grate may be turned on its support to free it of ashes and cinders.

35 D represents a tube that passes up through the center of the grate C, and a conical grate or frame, I, in the middle of the grate C. This grate or frame I may be turned or shaken by a lever, J, having a socket, J', that fits over the lower end of the tube D, and a lug, 40 J'', that fits between the cogs of a wheel, J', on and secured to the tube. The lever is shown in position in Fig. 1, and it will be seen that by moving it back and forth the grate or frame I, which is secured to and carried by the tube, will be shaken to free it of ashes and cinders. The bottom I' of this vertical grate I rests in a circular rabbet-groove, L, in the ring C'' of the grate C. (See Fig. 3.) The upper part of the grate consists of up- 45 wardly and inwardly inclined bars M, secured to the upper end of the tube D at top, and held in position lower down by rings N

N', the ring N' being connected by arms N'' to a central hub, N'', that surrounds the tube D above a hub, C', of the grate C.

55 The lower part or bottom of the grate consists of downwardly and inwardly inclined bars M', whose lower ends work in the rabbet.

O represents a fire-clay crown or cap extending horizontally from the top of this vertical grate upon every side. I prefer to make notches or grooves D' in the periphery of the crown or cap for the passage of the steam that is discharged through perforations P in the pipe or tube D, and escapes through the spaces between the bars M into the furnace to assist combustion. The steam is supplied to the tube through means of a pipe, S. The hot air from the ash-pit circulates up through 70 the grates, passing between the ring C'' and hub C' of the horizontal grate, and out between the bars of the vertical grate into the combustion-chamber; and its passage is also facilitated by the notches D' in the cap. The 75 tube preferably has perforations P' in its top, as well as lower down, for the passage of steam.

70 The lower ends of the bars of the vertical grate, fitting as they do in the rabbet-groove 80 L of the horizontal grate, prevent the bars, in connection with the rings N N', from being warped and drawn out of place by the heat.

85 The cap O prevents the fuel from pressing or lying close against the bars of the vertical grate, which would retard the passage of air and steam.

In Fig. 5 the vertical grate is shown applied to a horizontal grate formed to fit a horizontal furnace.

90 I claim as my invention—

1. A grate comprising a horizontal portion having a hub, concentric rings or partitions, and bars connecting the rings to the hub, a vertical portion having upwardly and inwardly inclined bars, downwardly and inwardly inclined bars, a ring or partition connecting the bars, a hub, and bars connecting the ring to the hub, and a tube by which the vertical portion is rotated on the horizontal portion, 95 substantially as set forth.

100 2. A grate comprising a horizontal portion having a hub and a rabbet, a vertical portion having upwardly and inwardly extending

bars, downwardly and inwardly extending bars supported in the rabbet, and a ring or partition connecting the bars and having a hub seating on the hub of the horizontal portion, and a tube having perforations and forming a pivot by which the vertical portion is rotated, substantially as set forth.

3. A grate comprising a horizontal portion having a hub, a vertical portion having a hub seating or supported on the hub of the horizontal portion, a tube having perforations within the vertical portion and perforations above the vertical portion, and means for connecting a steam-pipe with the tube, substantially as set forth.

4. A grate comprising a horizontal portion, a vertical portion, a tube passing entirely through said portions, having perforations for the escape of steam therethrough, and the crown supported on the top of the vertical portion, substantially as set forth. 20

5. A grate comprising a horizontal portion, a vertical portion, a tube, and a lever, the vertical portion being secured to the tube and rotated therewith, substantially as set forth. 25

MICHAEL A. FOSTER.
